UNITED STATES PATENT OFFICE

LORN CAMPBELL, JR., OF LAKewood, OHIO, ASSIGNOR TO THE HARRIS CALORIFIC COMPANY, OF CLEVELAND, OHIO, A CORPORATION OF OHIO

PROCESS OF MAKING BODIES

Application filed April 4, 1928. Serial No. 267,233.

This invention relates to a process of making bodies having a plurality of bores or passages therethrough, and particularly to bodies having bores or passages of such length, shape, or cross-sectional areas as render the production of such bodies difficult and/or expensive of accomplishment. Familiar instances of such bodies are unitary blowpipe tips which are employed for the cutting 10 of metal with oxygen. In making such tips, it has been found extremely difficult to provide the same with bores or passages for the mixture of oxygen with preheating gas and to make these bores or passages of the desired 15 cross-sectional area and to preserve the proper relation between them and the central bore for cutting oxygen. While my process is capable of use in the production of other types of perforated bodies, it will be described herein more particularly in connection 20 with the production of blowpipe tips of the character referred to.

In the drawings forming a part hereof, I have shown an original block or blank of 25 metal and the successive forms imparted thereto leading up to the production of a blowpipe tip such as described hereinbefore; also various forms of tips which may be produced in accordance with my process.

30 In the said drawings:—

Fig. 1 represents a side elevation of a piece or blank of ductile metal prior to the first operation thereon;

Fig. 2, a central, longitudinal, sectional view of the said blank after the same is provided with a central bore for cutting oxygen, and preheating mixture bores surrounding the central bore;

Fig. 3, a view similar to Fig. 2, and showing the mandrels or wires inserted into the bores;

Fig. 4, a view similar to Figs. 2 and 3, showing the final external shape given to the body, and also showing the mandrels or wires 45 still in place;

Fig. 5, a view similar to Fig. 4, and showing the finished tip; and

Figs. 6, 7, 8, 9 and 10, are views similar 50 to Fig. 5, showing modified forms of tips which may be produced by my process.

In order to produce a body, such as a unitary blowpipe tip, having the bores therethrough and free from the objections noted hereinbefore, I first take a piece or blank of ductile metal, such as copper, and preferably 55 cylindrical in shape, and of a length which will enable the central bore and the other bores to be drilled therethrough quickly and conveniently, while preserving the proper 60 relations between the central bore or passage and the bores or passages surrounding and spaced from the same. Such a blank is shown at A in Figs. 1, 2 and 3. This blank is provided in any convenient manner with a central longitudinal bore B for the cutting oxygen, and with a plurality of bores C grouped about the central bore and converging toward such central bore from the top to the bottom of the blank. The bores or passages 65 B and C will be of greater cross-sectional areas than the bore or passages desired in the final product. The size of the final bores or passages may be determined by inserting 70 into the bores, mandrels D of the desired shape and length, after which the blank is subjected to one or more operations whereby 75 it is elongated and its cross-sectional area varied in accordance with the shape which it is desired the final product shall assume.

In forming articles such as blowpipe tips, the lower portion of the body will usually be contracted or reduced in cross-sectional area to a greater extent than the upper portion, in order to impart the desired tapered shape 80 thereto. This elongation and reduction in cross-sectional area may be effected by any standard mechanical means, such as swaging, rolling, forging or drawing, the result being 85 to produce a body approximating more or less the final desired form or shape. This elongation and reduction in cross-sectional area of the body is accompanied by a corresponding reduction in the cross-sectional areas of the bores or passages; but the desired shape of such bores or passages is preserved by the mandrels inserted therein, which 90 mandrels are of such length as to project beyond one or both ends of the body as shown in Fig. 4, enabling them to be withdrawn at 95 the end of the shaping operation. However, 100

if desirable, the bores or passages remaining after removing the mandrels may be redrilled or may receive other further treatment. Where deemed necessary or advisable, the mandrels may be lubricated before insertion into the bores of the blank, which lubrication will facilitate their withdrawal after the final shaping operation.

After the operations above described, the body may be given further treatment to adapt it for its particular environment. For instance, in the case of a blowpipe tip, it will be necessary to impart to the body some details of form in order to adapt it to its seat in the blowpipe head. In the form shown in Fig. 5, the block is provided with an annular recess E which is adapted to receive the pre-heating gases from the blowpipe head and to distribute them to the bores C; also with a central projection F adapted to seat in the blowpipe head and to place the bore B in register with the bore or passage for cutting oxygen in said head.

In Figs. 6 to 10, inclusive, there are shown modified forms of blowpipe tips which may be produced in accordance with my process. Each of these tips comprises a body A, which is given an exterior shape according to the use and type of head to which it is to be applied. It will be noted that each of these tips is provided with a central bore B and with the bores C for preheating gases. In the case of each of the tips shown in Figs. 6, 7 and 8, one of the preheating gases is introduced into the upper ends of the bores C, and the other is introduced through ports G into the said bores at points spaced from the upper ends of the bores. In the form shown in Fig. 6, the preheating gas is supplied to the ports G from an annular channel H; in the form shown in Fig. 7, the combustible gas is supplied to the ports G from an annular channel H' in the top of the tip body; and in the form shown in Fig. 8, the gas is supplied to the ports G through an annular channel H² arranged somewhat similarly to the channel H in Fig. 6. In the form shown in Fig. 6, the top of the tip is tapered and the preheating gas which enters the top of the bore C is supplied thereto from an annular channel J, below a tapered head K which is adapted to fit a corresponding seat in the blowpipe head. In the form shown in Fig. 7, the cutting oxygen is delivered to the port B from a chamber L in the top of the tip. In the form shown in Fig. 8, the upper portion of the tip is threaded, as shown at M, and the central part of the tip is rounded, as shown at N, this end construction being given to the tip to enable it to be secured in operative relation to a particular type of head.

In Fig. 9, the upper end of the tip is of continuous frusto-conical shape, the upper ends of the bores C extending through the conical surface and the upper end of the bore

B extending through the upper base. In each of the forms shown in Figs. 3-9, inclusive, the tip is provided with a shoulder O which is adapted to be engaged by a shouleder nut or similar device for securing the tip in place.

In the form shown in Fig. 10, the upper central part of the tip is shown as extending a considerable distance above the body A and as being provided with a thread M' for securing the tip in place, while the bores C extend at their upper ends through a shoulder P at the base of such central extension.

Having thus described the invention, what is claimed is:—

1. The process of making a unitary body having a plurality of bores extending longitudinally therethrough, which consists in providing a blank of ductile metal with bores extending therethrough, swaging said body thereby to elongate the same and to reduce the cross-sectional area of the blank and also to reduce the cross sectional areas of the bores below the area required in the finished body, and drilling the said bores to the desired shape and cross sectional area.

2. The process of making a unitary body having a plurality of bores of a desired length, size and form extending longitudinally therethrough, which consists in first providing a blank of ductile metal with bores extending longitudinally therethrough, the said blank and the said bores being shorter and of greater cross-sectional areas than desired for the completed body and bores, inserting into said bores forms capable of giving to said bores a shape and dimensions approximating those desired in the final body, then elongating the said blank and the bores thereof and reducing the cross-sectional areas of said blank and said bores simultaneously, then removing the forms from the said bores, and drilling the bores to the final shape and dimensions.

In testimony whereof, I hereunto affix my signature.
